UNITED STATES PATENT OFFICE.

HARRY J. PERKINS, OF GRAND RAPIDS, MICHIGAN.

MARINE PROPULSION MECHANISM.

1,131,862.

Specification of Letters Patent. Patented Mar. 16, 1915.

Application filed January 31, 1914. Serial No. 815,620.

To all whom it may concern:

Be it known that I, HARRY J. PERKINS, a citizen of the United States, residing at Grand Rapids, in the county of Kent and 5 State of Michigan, have invented new and useful Improvements in Marine Propulsion Mechanisms, of which the following is a specification.

My present invention relates to marine 10 propulsion mechanism, and its object is to provide mechanism of that character which shall be simple and economical in construction and easy and efficient in operation. This and any other objects hereinafter appearing are attained by, and the invention finds a preferable embodiment in, the structure hereinafter described and illustrated by the accompanying drawings, in which:

Figure 1 is a side elevation of said structure: Fig. 2 is a vertical central section of the same: Fig. 3 is a like view of the lower part thereof: Fig. 4 is a transverse section on line 4—4 of Fig. 3: Fig. 5 is a top plan view of the tiller and a transverse section 15 of the rudder stock, crank shaft, etc: Fig. 6 is a fragmentary view of the same parts mostly in vertical central section: Fig. 7 is a transverse section of the rudder stock, crank shaft, etc., on line 7—7 of Fig. 3: Fig. 8 is a transverse section on line 8—8 of Fig. 6: Fig. 9 is a like section on line 9—9 of Fig. 6: Fig. 10 is a side elevation of the supporting frame: Fig. 11 is a fragmentary side elevation of a part of the same, 20 showing a variant construction: Fig. 12 is a vertical central sectional view of the exhaust silencer: Fig. 13 is a transverse section thereof on line 13—13 of Fig. 12: and Fig. 14 is a sectional view on line 14—14 25 of Fig. 12.

My marine propulsion mechanism is adapted to be removably attached to a boat 1 (indicated in dotted lines in Figs. 1 and 2), as by the supporting frame 2 straddling 30 the stern board 3 whereto it is clamped as by a suitable screw 4. The rest of the mechanism is adjustably carried by this supporting frame, so that it may be held in different positions vertically relative thereto, 35 by its supporting bolt 5 adapted to be inserted into any one of a series of orifices 6 in said frame, or to be passed through a slot 7 (as particularly shown in Fig. 11); and 40 also so that it may be held at the proper angular position relatively to the stern

board, as by the arm 8 pivoted on said frame and having a clamping nut 9.

The internal combustion engine is of common type, having a cylinder 10, fuel tank 11, piston 12, fly wheel 13 with cranking handle 14, engine shaft or crank shaft 15, etc.; bearings 16 for this shaft are carried within a supporting sleeve 17 borne by the engine frame 18; bevel gears 19 drive the propeller shaft 20 carrying the propeller 21. 65 Suitable pumping mechanism 22 operated by the cam 23 supplies cooling water through a flexible tube 24 to the water jacket chamber 25; the overflow water from this chamber runs through a pipe 26 to the exhaust silencer 27 where it meets the gases, etc., constituting the "exhaust" from the engine, conducted therefrom by the exhaust pipe 28. This exhaust silencer has a chamber 29 containing a bell 30, the inner wall 70 of the chamber and the external surface of the bell being provided with alternately disposed deflectors 31 so that the water and exhaust will in passing downwardly, be thoroughly commingled, thus to minimize the 75 noise of the exhausting of the engine, to which end the under-water discharge port 32 of the silencer also contributes. The rudder stock is a sleeve 33 surrounding and having its rotary bearing on the supporting 80 sleeve 17 and carrying the rudder blade 34 extending both above and below the propeller shaft; a geared segment collar 35 is carried by the rudder stock being clamped thereto as by a screw bolt 36. Pivoted at 85 37 on the engine frame is the tiller 38 having a geared segment 39 intermeshing with the segment 35 to turn the rudder.

Not confining myself to details of construction shown or described, I claim:— 95

1. In mechanism of the character described, a supporting frame having a plurality of orifices arranged one above another, means for securing said frame to a boat, an engine frame carrying an engine 100 and propeller and also a rudder, and a bolt adapted to support the engine frame and to pass through any of said orifices to hold the engine frame in a desired position vertically relatively to the supporting frame, the rudder having a swinging horizontal movement relatively to the engine frame. 105

2. In mechanism of the character described, an engine frame carrying an engine 110 and propeller, a vertical rotatable shaft for

driving the propeller by the engine, and a rudder stock carrying a rudder blade and rotatable for steering on bearings surrounding said shaft.

5 3. In mechanism of the character described, an engine frame carrying an engine and propeller, a vertical rotatable shaft for driving the propeller, a rudder stock rotatable for steering on bearings surrounding 10 said shaft and having a rudder blade extending below the propeller's axis.

4. In mechanism of the character described, an engine frame carrying an engine and propeller, a vertical rotatable shaft for

driving the propeller, a rudder stock carrying a rudder blade and rotatable for steering on bearings surrounding said shaft and having a segmental gear, and a pivoted tiller having a segmental gear, meshing with the rudder stock's said gear to rotate the 15 20 same.

In testimony whereof I have hereunto set my hand in presence of two subscribing witnesses.

HARRY J. PERKINS.
